UNITED STATES PATENT OFFICE.

WILLIAM W. COOPER, OF HARRISBURG, PENNSYLVANIA.

RAILROAD-TIE.

1,139,753.

Specification of Letters Patent. Patented May 18, 1915.

Application filed December 23, 1913. Serial No. 808,319.

To all whom it may concern:

Be it known that I, WILLIAM W. COOPER, a citizen of the United States, residing at Harrisburg, in the county of Dauphin and 5 State of Pennsylvania, have invented certain new and useful Improvements in Railroad-Ties; and I do hereby declare the following is to be a full, clear, and exact description of the invention, such as will enable others skilled in the art to which it 10 pertains to make and use the same.

This invention relates to new and useful improvements in railway ties, and has for its principal object the provision of a tie 15 which will be substantially indestructible.

Another object of my invention is the provision of a novel combination and arrangement of parts which will prevent the rails which are secured to the ties, from spreading 20 and thus causing accidents.

A further object of my invention is to provide a durable tie which will be composed of a piece of sheet metal bent in the form of a rectangular casing and filled with 25 concrete, thus forming a tie which will be capable of resisting the elements.

A still further object of my invention is the provision of a novel means for absorbing the shock due to the passage of heavy 30 traffic over the road bed.

A still further object of my invention is the provision of a novel combination and arrangement of parts by which the rail is firmly clamped in place on the tie without 35 the necessity of using spikes or bolts.

With the above and other objects in view, I will now proceed to describe my invention, which consists of a novel combination and arrangement of parts to be more fully 40 hereinafter described.

Figure 1 is a perspective view of a fragment of the tie showing the same as it would appear with a portion of the rail in place. Fig. 2 is a longitudinal sectional view 45 through the tie showing the supporting block for the rail and the rail locking wedge in section, and Fig. 3 is a longitudinal sectional view taken on line 3—3 of Fig. 2.

Referring more particularly to the drawings by numerals, 1 indicates the railroad rail of the usual construction comprising a head 2, web 3, and the flanges 4 and 5 respectively. This rail above described, is preferably placed so that the flange rests 55 upon the shock-absorbing block, as will more fully hereinafter described.

The tie, which is indicated generally by the numeral 6 is preferably formed of a suitable sheet metal casing 7. This sheet metal casing is preferably rectangular in cross section and is adapted to be filled with concrete or a like substance which will make the tie substantially integral. This plastic material is indicated generally by the numeral 8 which may be composed of a suitable aggregate of any of the standard formulas. Near each end of the tie and suitably secured in a recess, I preferably provide the blocks 9 which are of wood, asphalt or any other suitable resilient material which will take up the shock caused by the traffic over the road. The upper surfaces 10 of the blocks are preferably slightly below the upper surface of the tie, as clearly illustrated in Fig. 2, to form a rail seat in which the flange 75 of the rail is adapted to rest when the device is in use.

Immediately adjacent the recesses in which the blocks 9 seat, I preferably provide the transversely extending bolt 11 which extends beyond the lateral extremities of the tie and forms pivotal connections for the rail flange clamping means, which will be more fully hereinafter described. The rail clamping means, above referred to, which is indicated generally by the numeral 12, preferably comprises the body portion 13 having the flange engaging extensions 14 formed integral therewith. Formed integral with the portion 13 and extending at 80 substantially right angles to the flange engaging extensions 14, I preferably provide the angular extension 15 which is adapted to engage the wedge block 16 having the wedge face 17 formed thereon, which is adapted to be driven through a pair of rectangular apertures indicated by numerals 18 and 19 and thereby clamp the rail firmly against the block 9 when the device is in use. Should it be so desired, it is to be understood that 85 the block 20 may be placed beneath the block 9 to afford further support for said block.

It will be clearly seen from the foregoing that when it is desired to make use of my improved tie, the same is placed on the road 90 in the usual manner with the rail lying upon the block 9. The rail is secured in place by means of the clamping member 12 through the action of the web engaging extensions 14 which is tightly forced against the flange of 95 the rail through the action of the wedge member 16 the face of which engages the 100

angular extension 15 and forces the same over as the wedge is driven in place.

While in the foregoing I have shown and described the preferred embodiment of my invention, I wish it to be understood that I may make such changes in the combination and arrangement of parts as will fall within the scope of the claim herewith submitted.

Having thus described my invention, I

10 claim:

A rail tie comprising a hollow rectangular body formed of sheet metal, the top and side walls being cut away near each end to permit a rail to seat therein, transverse ribs 15 formed on the inside of the bottom wall of

the tie at points directly beneath the end walls of the recesses, cushioning blocks arranged to seat within the tie between the ribs, bearing blocks arranged to rest on the cushioning blocks and fill the space between 20 the upper faces of the cushioning blocks and the under faces of the top wall of the tie, and a plastic filler within the tie.

In testimony whereof I affix my signature in presence of two witnesses.

WILLIAM W. COOPER.
